UNITED STATES PATENT OFFICE.

WALLACE P. HOUGH, OF PITTSBURGH, PENNSYLVANIA.

CURTAIN-STRETCHING FRAME.

1,151,594.

Specification of Letters Patent. Patented Aug. 31, 1915.

Application filed April 17, 1914. Serial No. 832,413.

To all whom it may concern:

Be it known that I, WALLACE P. HOUGH, a citizen of the United States, residing at Pittsburgh, in the county of Allegheny and State of Pennsylvania, have invented certain new and useful Improvements in Curtain-Stretching Frames, of which improvements the following is a specification.

My invention has for its objects, to provide a curtain stretching frame, of the knock-down type, wherein the longitudinal side members thereof are each formed of sections adapted to be connected or disconnected to lengthen or shorten the frame for convenience and economy of space to suit the lengths of curtains, with a connection for the sections of each of said members, whereby they may be rigidly and securely locked to one another, disconnected or folded upon one another to save space when not in use.

With the above objects in view, the invention consists in certain features of construction, in certain parts and combination of parts, as will be hereinafter more specifically set forth in this specification and particularly pointed out in the appended claims.

In describing the invention in detail, reference is had to the accompanying drawings, forming a part of this specification, wherein like detail parts are designated by like numerals for convenience in referring to said parts, said drawings representing the following views:

Figure 1 is a front elevation of the frame, as it would appear when set up for service. Fig. 2 is an enlarged end elevation thereof. Fig. 3 is an enlarged front elevation of a portion of one of the side members of the frame, showing my improved connection for the sections thereof. Fig. 4 is a plan of the same. Fig. 5 is an end elevation thereof, in section. Fig. 6 is a plan of the portion of one of the side members, as it would appear when its sections are folded. Fig. 7 is an enlarged end elevation of a portion of the frame, and supporting leg, showing my improved connection therefor to limit the adjustment of and lock the leg in extended position. Fig. 8 is a plan view thereof, partly in section. Fig. 9 is an end elevation of a portion of the frame, showing the leg folded thereupon.

In said drawings, I have shown the frame proper, as comprising the two like side

members 1 and 1, each formed of two sections; the two like end members 2 and 2, each having a leg 3 pivotally attached thereto at its upper end by a screw 4, said end members being laterally adjustable along and held in adjusted position to the side members, by a fixed clamp 5 at the upper end of each, and by a vertically adjustable clamp 6 on the lower end of each. There is also a vertically disposed bar 7 secured to the upper side member by a screw 7' and secured at its lower end to the lower side member by a bolt 8 passing therethrough and through the slot 8' in said bar, a thumb-nut 9 being provided on said bolt. The side, and likewise the end members of the frame, each have the usual pins 10 arranged along their inner edges to secure the curtain thereto.

My improved connection for the two sections constituting each side member, 1 and 1, comprises a plate 11, preferably of L shape in cross-section, and preferably extending through the slots 12 in the meeting ends of the sections, said plate being fixedly attached at one end to one of the sections by screws 13 and 14. This plate has a recess 15 formed in the extreme end of the portion thereof which projects to the other movable section, and in the body portion thereof a diagonally disposed opening 16, preferably radial in form, there being also a recess 17 formed in the edge of the free portion of said plate. The movable section of the side member to be attached to the plate fixed to the other section, has openings formed therethrough registerable with recess 15 and opening 16 of the plate, through which extend bolts 18 and 19, provided with thumb nuts 20 and 21, respectively.

In practice, when the side members, 1 and 1, are employed full length, the thumb nuts 20 and 21, of the bolts 18 and 19, are screwed down tightly, thus holding the sections rigidly to one another. When the frame is taken down to be stored away, the thumb nuts 20 and 21 are loosened up, the then loose or movable section of the side member, is slightly adjusted, in the direction of its length, so as to cause the bolt 18 to pass out of the recess 15 of the plate, after which operation the said section is turned about the bolt 19 and folded flush with and upon the other section, as shown in Fig. 6, the elongated opening 16 in the plate permitting such turning of the member about the bolt

19, and when so folded the recess 17 forms a clearance space about the bolt 18. When the frame is to be set up for the drying of short curtains, the bolt 18 is removed and the section to which it was applied detached.

My improved folding brace for and to limit the adjustment of and lock the leg in extended position, comprises a plate 22 having downwardly extended flanges 23 and 23' formed thereon, which flanges also project forwardly to and pass each side of the end member of the frame to which the leg is pivotally attached and are pivotally attached to said member by screws 24 and 25. The side flange 23 of said plate, has an elongated opening or slot 26 formed therethrough, terminating at its far end in a shoulder 26', making said slot somewhat the shape of the letter L, through which slot passes a pivoting screw 27 fixed to the leg.

In practice, when the leg is extended, the pivoting screw 27 operating in the slot 26 limits the extension of said leg, and when the plate 22 is slightly depressed at its rear end said screw is caused to enter the shouldered portion 26', thus locking said leg in its extended position and preventing possible closure of the leg and consequent overthrowing of the frame rearwardly, and as the plate 22 extends entirely across the rear of the end member 2 it forms a rigid connection and prevents accidental overthrow of the frame longitudinally. To fold the leg flush with the end member 2, the brace plate 22 is slightly elevated at its rear, thus disengaging the shouldered portion of the slot with the pivotal screw 27, after which said leg may be readily folded flush with the member 2, and causing the body of the plate to engage flush with the rear surface of said member, as shown in Fig. 9.

Having thus shown and described my invention, what I claim and desire to secure by Letters Patent, is:

1. In a curtain stretching frame, side members therefor, each formed of sections connected one to the other at their abutting ends by a plate of L shape in cross-section fixed to and projecting beyond the end of

one section and to which the other section is movably connected, the projecting portion of said plate having an elongated diagonally-disposed opening formed therethrough and also having a recess formed in its extreme end, and bolts provided with thumb nuts carried by the movable section, one of said bolts passing through the opening in the plate and the other through the recess in the end thereof, adapted, when tightened up, to rigidly secure the movable section to said plate, and when loosened, to permit said movable section to be adjusted longitudinally on said plate disengaging the one bolt at the recessed portion thereof and turned about on the other bolt to a folded position upon the other section, said sections being each slotted longitudinally at their abutting ends wherein the said plate is disposed.

2. In a curtain stretching frame, side members therefor, each formed of sections connected one to the other at their abutting ends by a plate of L shape in cross-section fixed to and projecting beyond the end of one section and to which the other section is movably connected, the projecting portion of said plate having an elongated diagonally-disposed opening formed therethrough and also having a recess formed in its extreme end, and bolts provided with thumb nuts carried by the movable section, one of said bolts passing through the opening in said plate and the other through the recess in the end thereof, adapted, when tightened up, to rigidly secure the movable section to said plate, and when loosened, to permit said movable section to be adjusted longitudinally on said plate disengaging the one bolt at the recessed portion thereof and turned about on the other bolt to a folded position upon the other section.

In testimony whereof, I affix my signature, in presence of two witnesses.

WALLACE P. HOUGH.
